UNITED STATES PATENT OFFICE

McCLELLAND BARCLAY, OF NEW YORK, N. Y.

DESIGN FOR AN ASH JAR

Application filed July 13, 1931. Serial No. 40,534. Term of patent 14 years.

To all whom it may concern:

Be it known that I, McCLELLAND BARCLAY, a citizen of the United States, residing at No. 730 Fifth Avenue, New York city, in the county of New York and State of New York, have invented a new, original, and ornamental Design for an Ash Jar, of which the following is a specification, reference being had to the accompanying drawings forming part thereof.

I claim:

The ornamental design for an ash jar, as shown.

McCLELLAND BARCLAY.
